UNITED STATES PATENT OFFICE.

JESSE S. WHEELAND, OF SAN FRANCISCO, CALIFORNIA.

RADIO WAVE SWITCH.

Application filed January 4, 1928. Serial No. 79,175.

This invention relates to a switch especially intended for the purpose of cutting in and out of circuit the resistances of coils used in radio receiving apparatus, and it is intended for the purpose of acting as a wave control switch.

An object of the invention is to provide means whereby the switch will have a plurality of movable contacts which will enable a varied series of contacts to be readily made.

Another object of the invention is to provide a switch which is constructed in a form to be easily assembled from the front of an ordinary radio set, either the contacts be operated by the rotation of a knob, or by pushing and pulling an arm to turn the contacts to the desired positions.

An embodiment of the invention is shown in the accompanying drawings in which the same reference numeral is applied to the same portion throughout the several figures of the drawings, and of which there may be modifications:

Figure 1 is a transverse sectional view of the switch taken on the line 1—1 Figure 2.

Figure 2 is a longitudinal sectional view of the switch.

Figure 3 is a plan view of the switch.

Figure 4 is a diagrammatic view of the switch contacts, showing a series of coils connected thereto.

Figure 5 is a transverse sectional view of a modified form of the switch in which a handle for operating the contacts is pushed inwardly or pulled outwardly, as may be desired.

Figure 6 is a longitudinal sectional view of the switch on the line 6—6 Figure 5.

Figure 7 is a view of the switch in elevation looking from the back of the board upon which it is mounted.

Figure 8 is a transverse sectional view of a slightly modified form of the switch on the line 8—8, Figure 9.

Figure 9 is a longitudinal sectional view of Figure 8.

The switch contacts are mounted upon a cylindrical shell made of non-conducting material, which has the ends 2 and 3 for the support of a stub shaft 4, and a stub shaft 5, on which latter the knob 6 is mounted. Yokes 7 and 8 on the two shafts 4 and 5, carry a bar of non-conducting material 9 to which the spring contacts 10, 11 and 12 are connected.

These contacts are arranged to pass over the heads of a series of rivets 13, 14 and 15, three rows of said rivets being made use of, so as to give nine possible combinations. 60

The switch itself is secured to the front 17, of the radio set by means of two small bolts 18 and 19. In the present example a series of coils 20 are connected to the three back rivets of the switch by means of wires 21 and 22 and 23, but, of course, as many other wires may be used as may be desired and different combinations provided.

In the form of the invention shown in Figures 5 to 7 inclusive, there is a cylindrical shell 30 which has two ears 31—32 for securing it to the front board 33 of the radio set, within the shell there is a bar of non-conducting material 34, which is pivotally mounted by means of two cap screws 35 and 36, and the bar has an operating spring 37 secured thereto which is connected to a slideable rod 38 which has the operating knob 39 on its outer end. 70 75

The bar 34 carries three contact springs 40—41 and 42 which springs are arranged to contact in pairs with the rivets 43—44 and 46 of which there are three rows as indicated in Figures 6 and 7. The wires may be connected with the rivets in any desired order to give the necessary permutations of resistants with the movement of the contact holding bar. 80 85

In the form of the invention shown in Figures 8 and 9 the cover for carrying the contacts is illustrated at 50, and it is substantially semi-cylindrical, with the ends 51 and 52 to bear upon the front board of the radio set, or other wall 53 to which the switch is connected. 90 95

The ears 54—55 provide means whereby the cylindrical shell may be connected to the front board 53. The front board has a slot at 55 through which an operating handle 56 projects. This operating handle may be of any suitable material, and has pivot pins 57, 58 which are held against the front board 53 by means of a plate 59. A bar 60 made of insulating material is connected to the handle 56, and it carries the three contact springs 61, 62, 63. The semi-cylindrical shell has nine contacts, the same as the other form of the switch, in rows of three each, said contacts being shown at 61, 62 and 63. 100 105

Having thus described my invention, what I desire to secure by Letters Patent of the United States is as follows, but modifica-

tions may be made in carrying out the invention as shown in the drawings and in the above particularly described form thereof, within the purview of the annexed claim.

- 5 A radio wave switch comprising a semi-cylindrical shell of insulating material, electrical contacts, spaced apart longitudinally and transversely and arranged in rows on the inside surface of said shell, contact
10 springs for each transverse row adapted to span the space between any two of said

longitudinal rows, said springs adapted to be mounted on an insulating bar, an operating handle having side projecting bearing members, bearings for said members, means 15 for attaching said insulating bar to said operating handle.

In testimony whereof I have hereunto set my hand this 22d day of December, A. D. 1925.

JESSE S. WHEELAND.
